UNITED STATES PATENT OFFICE

2,217,932

TREATMENT OF TOBACCO

Jesse C. McCorkhill, Jacksonville, Fla., assignor,
by mesne assignments, to The Guardite Corporation, a corporation of Illinois

Application August 17, 1939, Serial No. 290,701

2 Claims. (Cl. 131—140)

This invention relates to the treatment of tobacco and particularly to a process for moistening tobacco.

One object of this invention is to provide a process of treating tobacco, wherein the tobacco is subjected to the action of carefully regulated moisture in an inclosure so as to render the tobacco pliable and moist.

Another object is to provide a process for treating tobacco especially adapted for the manufacture of cigars, wherein the tobacco leaves, either in the form of "hands" or "bales" are treated by being placed in a partially evacuated inclosure and subjected to the action of water vapor at a suitable temperature.

Another object is to provide a process for treating tobacco comprising impregnating the tobacco with moisture in a partial vacuum.

Another object is to provide a process for treating tobacco leaves, particularly for cigar-making purposes, wherein the dry tobacco is placed in an inclosure from which the air is then partially removed, the tobacco being then subjected to treatment with steam, supersaturated with water. 25 The tobacco is then subjected to partially saturated live steam for a short period in an inclosure, from which most of the air has again been removed.

This application is a continuation-in-part of 30 my co-pending applications Serial No. 135,092, filed April 5, 1937; Serial No. 159,745, filed August 18, 1937; and Serial No. 282,237, filed June 30, 1939.

In the drawings:

35 Figure 1 is a central vertical section, partly in side elevation, of one form of apparatus of this invention, which may also be used for carrying out the process of this invention, with the end closure thereof removed.

40 Figure 2 is a right-hand end elevation of the apparatus shown in Figure 1, with the end closure in position.

Figure 3 is a vertical cross section along the line 3—3 in Figure 1.

45 Figure 4 is a left-hand end elevation of Figure 1.

Figure 5 is an enlarged side elevation, partly in section, of the forward end of the apparatus, showing the means for facilitating the loading 50 thereof with tobacco.

Figure 6 is a cross section along the line 6—6 in Figure 1.

Figure 7 is a side view of the measuring tank and heating arrangement associated with Figure 55 1.

Figure 8 is a modification of a portion of Figure 1, showing means for automatically controlling the temperature of the steam by a temperature-responsive automatic steam valve.

Figure 9 represents a modification of the method of introducing water and is a diagrammatic side elevation of the tank in which only the water distribution system is illustrated, the rest of the piping not being shown for the purposes of clarity.

Figure 10 is a cross-section along the line 10—10 in Figure 9.

In general, the process of this invention consists in treating tobacco with carefully regulated moisture in a partial vacuum under a sufficiently high temperature to render the tobacco pliable and moist.

Hitherto, it has been necessary to sprinkle the tobacco leaves and leave them to soak over night in order to remove the excessive dryness thereof. 20 Ordinarily, tobacco is received at the factory either in the form of bales or "hands," consisting of a number of leaves bundled together and tied at the stem end only. This tobacco, when thus received, is usually in a very dry condition, and 25 accordingly is very brittle and easily disintegrates. In order to use the tobacco for making cigars, the ordinary treatment has included sprinkling the dry bales by hand, letting them stand for many hours in order to distribute the 30 moisture properly, and, then after casing, treating the tobacco in sweat-rooms for a period of two to six weeks. These bales are large tightly-packed bodies of tobacco, weighing several hundreds of pounds. If they are unpacked in their 35 usual dry condition, there is excessive breakage. On the other hand, the insulating value of the tobacco in the bales is so high that cooling thereof or heating thereof occurs only very slowly under atmospheric pressures.

The present process and apparatus enable the tobacco to be treated immediately to supply the proper amount of moisture so as to render it pliable and at the same time to treat it by means of heat and moisture in such a manner as to remove certain undesirable oils and gums, and thereby to eliminate this long period previously thought necessary for sweating the tobacco leaves in sweat-rooms.

Referring to the drawings in detail, Figure 1 50 shows a preferred embodiment of apparatus for carrying out the purpose of this invention, and also adapted to be used in subjecting the tobacco to the process of the present invention. This apparatus consists of an air-tight tank 10 having 55

a rear end wall 11, permanently secured thereto as by welding, so as to form an air-tight joint at the junction 12. The forward end of this tank 10 is provided with a strengthening band 13 and 5 a gasket 14, surrounded by a ring-shaped angle member 15. Arranged to engage the portions 13 and 15 is an end closure member 16 (Figure 2) having securing clamps 17 arranged at intervals around its periphery. The clamps 17 have incorporated therewith screw members 18, whereby the clamps 17 may cause the end closure to engage the end of the tank 10 in the air-tight joint.

A handle 19 is also mounted upon the end 15 closure 16, the latter being supported by rods 20 anchored to brackets 21, as by the nuts 22, the brackets 21 being secured as by welding to the end closure 16. At their upper ends the rods 20 are secured to a cross bar 23 by nuts 24, the 20 cross bar itself being, in turn, attached as at 25 to a U-shaped supporting member 26, with a bolt 27 passing therethrough. Arranged to hold the supporting member 26 is a swinging arm 28 having a vertical shaft 29 and a supporting 25 brace 30. The shaft 29 of the swinging arm 28 is mounted in a support 31, which is capable of being secured to an upright member, such as a post or pilaster (not shown), as by bolts or screws passing through the holes 32. The swinging arm 30 28 and the member 26 thus are adapted to sustain the weight of the end closure 16 and to enable it to be swung to one side when it is desired to make the tank accessible for loading, unloading or inspection. Arranged immediately beneath the 35 end closure 16 is a drip pan 33.

The bottom of the tank 10 is provided with a runway 34 (Figure 3) which terminates at its forward end in an angled supporting member 35 (Figure 1). This supporting member 35 serves 40 as a rest for a swinging bridge member 36, hinged as at 37 to an inclined approach member 38. The members 36 and 38 are strengthened by the members 39 and 40, secured to the under-sides thereof. Immediately beneath the hinge connection 37 is arranged a supporting member 41, resting upon the floor. The bridge member 36, during the loading or unloading of the tank, occupies the position shown in Figures 1 and 5, with its forward end resting upon the ledge of 45 the member 35. The end closure 16 in the meantime has been swung to one side, as shown in Figure 5. The tank 10, on its inner walls, is provided with a pair of longitudinally disposed troughs 42, secured to the walls in a water-tight manner, as by welding. These troughs 42 are 50 arranged to receive water which may condense on the inner walls of the tank 10, and also to receive water which is deliberately supplied thereto by means of the pipe 43 (Figures 1 and 3) 55 having a valve 44.

Beyond the valve 44 the pipe 43 is connected to a water supply line 45 by means of the T-connection 46. The water supply line 45 is provided with a pair of valves 47 and 48, and a T-connection 49. From the T-connection 49 the pipe 50 runs to a mixing connection 51, where it joins the steam pipe 52. The steam pipe 52 is supplied 55 at intervals with the valves 53 and 54. From the mixing connection 51 a pipe 55 runs to a T-connection 56, the T-connection 56 leading, by means of a short pipe 57, to a port in the walls of the tank 10. Beyond the T-connection 56 the pipe 55 may be placed in communication with the atmosphere by opening the valve 58. On 60 opposite sides of the mixing connection 51 the

pipes 52 and 55 are supplied with T-connections 58 and 60, respectively, for the connection of a by-pass line 61, having a by-pass valve 62 therein.

At the T-connection 63 the steam pipe 52 is connected to the steam supply pipe 64, the latter 5 connected to a suitable boiler or other source of high pressure steam. In Figure 1 the continuation of the pipe 52 to the left of the T-connection 58 is shown in side elevation, together with the valve 53, the T-connection 63 and the 10 pipe 64, because this showing renders the disclosure of the piping clearer than if the piping were omitted, due to the breaking away of the tank at this point. The true relationship is clearly seen from Figure 4. Beyond the valve 15 53 the pipe 52 passes downward and is connected at the T-connections 65 (Figure 4) to the cross pipe 66 leading to the steam heating pipes 67 connected to the opposite ends thereof.

The steam pipes 67 pass through the end wall 20 11 of the tank 10 and lie within the troughs 42. At the rearward ends of the troughs 42 (Figure 3) the steam heating pipes 67 emerge from the troughs and pass downwardly, beneath the runway 34, near the bottom of the tank 10. The steam heating pipes 67 continue along the floor 25 of the tank, beneath the runway 34, and terminate in the connection 68, from which the return pipe 69 leads through the end wall 11 to the steam trap 70, from which the condensate 30 line 71 conveys condensed water back to the boiler. The bottom of the tank is also provided with an outlet port 72 having a drain pipe 73 connected thereto, the latter including a drain valve 74. By opening the drain valve 74 any 35 surplus water accumulated in the bottom of the tank may be drained away. Similarly, the troughs 42 are provided with an interconnecting drain pipe 75 (Figure 3), having a downwardly extending drain line 76 connected thereto at the 40 T-connection 77, and containing the drain valve 78. By opening the drain valve 78 the troughs 42 may be drained of any water, this draining being advisable at the beginning of the process 45 after the process has been previously carried out.

For the purpose of supplying refrigerating fluid the refrigerating coils 79 are provided. These coils 79 consist of pipes running to and fro lengthwise of the tank 10 and connected at their outer extremities 80 and 81, respectively, 50 with the refrigeration cross lines 82 and 83, connected as at 84 and 85 with the refrigeration inlet and outlet lines 86 and 87, respectively (Figure 4). A refrigeration valve 88 serves to regulate the admission of refrigeration fluid to 55 the refrigerating coils 79. Running lengthwise of the tank 10, immediately beneath the uppermost portion thereof, is a fluid line 89 provided at intervals with nozzles 90 and having a valve 91 immediately beyond the point where the line 60 89 emerges from the tank 10. This line 89 and its nozzles 90 serve for the distribution of casing fluid or other fluids.

Connected to a port in the wall of the tank 10 is the vacuum pipe line 92, containing a 65 valve 93. The vacuum pipe line 92 is connected to an evacuating apparatus, such as an air exhausting pump for the purpose of removing the air from the tank after the end closure 16 has been clamped thereto. The moisture admitted 70 through the short pipe 57 from the connection 56 is prevented from impinging directly upon the tobacco by means of the baffle plate 94, secured to the inner wall of the tank 10. A thermometer 95 and a pressure gauge connection 96 are also 75

supplied (Figure 6) for indicating the temperature and pressure existing within the tank 10.

In the operation of the apparatus, the tobacco, if in the form of bales, is placed upon a supporting rack structure 97 having shelves 98 for receiving the bales 99. The rack 97 rests upon a portable platform 100 (Figure 1), and the whole assembly may be transported by means of a portable lift truck of any conventional type. In one suitable type the lift truck is inserted beneath the portable platform 100 and then raised so that it lifts the platform off the floor and enables the entire assembly to be moved by means of the truck. If the tobacco is in the form of leaves or "hands" these are placed in boxes or crates, the crates being open or latticed to permit the free passage of the moisture and other treating materials. These crates are then merely placed on top of one another, preferably two to each platform 100, the framework or rack 97 being dispensed with.

Thus the loaded platforms 100 are placed on the trucks and the latter rolled up the incline 38 and bridge member 36 into the interior of the tank 10. The platform 100 is then lowered so as to rest upon the runway 34, whereupon the truck is removed and taken to the loading station for another load. In this manner the tank may be loaded with tobacco, beginning with the inner end of the tank and ending at the outer end with the final load. After the truck has been removed from beneath the final load, the bridge member 36 is swung upwardly about its hinge connection 37 until it occupies the dotted position shown at 36a in Figure 5. When this has been done, the end closure 16 is swung on its supporting arm 28 and shaft 29 and urged by the clamps 17, 18 into an air-tight position engaging the front gasket 14 of the tank.

In the modification shown in Figure 9, water is supplied to the tank through a manifold 143, extending longitudinally of the tank. This manifold is provided with a series of spaced distribution pipes 143a, the ends of which are provided with suitable nozzles. These nozzles have not been illustrated in detail because their construction is unimportant. In fact, best results have been obtained by the use of small openings of say $\frac{1}{4}$ to $\frac{1}{8}$ inch in the ends of the pipes. These openings may be directed in such a manner as to tend to lead the water into the trough 42 which may be done either by pointing the openings 144 in the direction of the trough or by directing the openings toward the wall of the tank adjacent the openings. It is preferred, however, generally to direct the opening toward the tobacco itself.

Air is withdrawn from the tank 10 by the vacuum pump 97, through the pipe 92 having the relief valve 98, and discharged through the pipe 99 until an absolute pressure of less than one-half inch of mercury is reached. Steam between 40 and 80 pounds pressure from the pipe 64 is then supplied with water in an amount more than required to saturate the steam just before being admitted to the tank 10. The temperature, period of treatment and degree of super-saturation are varied according to the kind and quantity of tobacco under treatment, so as to soften the tobacco.

With certain kinds of tobacco it is undesirable to go above a temperature of 120° F., whereas with others it is undesirable to go above 160° F. In general, the treatment will bring the temperature of the tobacco within the range of 120 to 160 degrees. A temperature of 140° has been

found satisfactory in most instances except for the extremely heat-sensitive tobaccos. The pressure within the tank under these conditions will be in the neighborhood of 3½ to 10 inches of mercury absolute, and at 140° will be about six inches absolute.

In general, however, temperatures of 165° to 190° have no deleterious effects upon tobacco.

The tank is maintained at this temperature between fifteen and forty-five minutes by an automatic steam control valve 53c under the control of a thermally-responsive device 53d (Figure 8), and having a by-pass line 53e with a valve 53b. Meanwhile, hot water is supplied to the troughs 42 through the pipes 43 and 45 from a steam-heated water heater 700 (Figure 7), which, in turn, receives water through the pipe 101 and valve 102 from the measuring tank 103. The latter is heated by a steam coil 104, which receives steam from the steam line 64 by way of the pipe 105 and valve 106. The valve 102 has a graduated dial to permit reproduction of a given setting representing a given rate of flow. The water heater 700 receives steam by way of the pipe 107 and valve 108, and discharges into the pipe 109 leading to the steam trap 110. The tank 103 receives water through the pipes 111 and 112, and compressed air through the pipes 113 and 114 containing the valve 115 and pressure gauge 116a. A valve 116 permits discharge of the air through the pipe 117 while refilling the tank 103. The tank 103 is equipped with gauge glasses so that the amount of water supplied to the heater and thence to the troughs 42 may be accurately predetermined. When the water is allowed to pass from the measuring tank to the water heater at a very slow rate, the heater will completely vaporize the water, especially at the subatmospheric pressure existing within the tank 10. In this manner the hot water may be supplied through the pipe 43 in the form of low pressure, low temperature steam. High pressure steam may also be admitted in limited quantities through the short pipe 57, this being prevented from striking the tobacco directly by means of the baffle plate 94 (Figure 6). The high pressure steam is supersaturated with water supplied at the mixing connection 51 from the pipe 50, which is connected to the water line 45 at the T-connection 49. Where it is desired to supply steam directly to the interior of the chamber, without supplying it to the heating coils 66, the valves 53 and 54 may be closed and the valve 62 opened, to permit the steam to flow through the by-pass line 61 to the connection 55 and pipe 57, directly into the interior of the tank 10.

Steam passed from a boiler into a tank at a sub-atmospheric pressure or partial vacuum will become super-heated and cause the temperature of the tank and contents to rise to a higher temperature than is desirable before a sufficient amount of moisture has been admitted in the form of steam. In order to counteract the super-heating effect, water is admitted in the manner previously described, either into the troughs 42 or directly into the steam as it flows into the tank 10 through the mixing connection 51 and pipe 57. Thus the steam may be used either to supply heat alone through the heating coils 67, or to supply both heat and moisture through the short pipe 57. The by-pass line 61 provides a more rapid means for admitting steam to the interior of the tank, where the particular process 75

does not require water to be added at the mixing connection 51.

When the troughs 42 are filled with water, in the manner stated, this water is vaporized by 5 means of the steam coils 67 passing through the troughs. This water in the troughs, if not accumulated in a sufficient amount of condensation on the walls of the tank, may be added by 10 means of the pipe 43. Water condensed on the walls of the tank below the troughs 42 flows to the bottom of the tank, beneath the runway 34 or floor, where it is subjected to the heat of the steam coils 67 as they continue along the floor 15 of the tank. This water is thus re-vaporized by the portion of the steam coils lying on the bottom of the tank.

After the treatment has been carried out for a sufficient length of time the steam and water are shut off and the valve 58 may be opened to 20 admit air to the interior of the tank. After this is done the end closure 16 is removed and the tobacco withdrawn from the tank. When this tobacco is removed it is completely impregnated with moisture and is in a soft and pliable 25 condition.

The tobacco may then be allowed to stand from eight to twenty-four hours, after which it is again placed in the tank 10 and subjected to an additional steaming treatment after again 30 producing a vacuum having an absolute pressure between 1½ and 2 inches of mercury. The tobacco may, however, be discharged or cased after the re-evacuation has cooled it, without further heating. The heat-treatment herein 35 described may, however, be performed upon the tobacco while it is still in the container and without breaking the vacuum or permitting the tobacco to stand. The standing is simply for the purpose of uniformly distributing the moisture through the tobacco and may be accomplished by repeating the steps of the process. The standing does not greatly affect the temperature of the tobacco on the inside of the bale, which remains substantially at the point to which 40 it was originally heated. Only the outside of the bale cools somewhat during the standing.

The tobacco, either with or without standing, is subjected to the subsequent evacuation just described, which reduces the temperature of the 50 tobacco by boiling some of the excess moisture which has been added during the previous step. To the extent that the tobacco is cooled during standing, if it has been allowed to stand, there is a saving of moisture because some of the cooling 55 has been carried out by contact with cool air or radiation, rather than by evaporation of moisture. To this extent the standing period results in a benefit over immediate evacuation. Where time is important, however, this advantage may sometimes be disregarded.

The tobacco, after cooling by re-evacuation, is subjected to a second steaming operation, which is performed with partly saturated live steam for a period of thirty to fifty-two minutes, 60 according to the particular type of tobacco under treatment. The valve 58 is then again opened to admit air and destroy the vacuum, after which the end closure 16 is again removed and the tobacco withdrawn from the tank. The tobacco 65 is then shaken out and is ready for stripping. This process thus eliminates the expensive sprinkling of dry bales by hand, and the long periods

of allowing them to soak in order to distribute the moisture throughout the leaves. The process of this invention also eliminates the necessity of placing the tobacco in sweat-rooms for a period of two to six weeks after casing.

When employing the modifications shown in 5 Figures 9 and 10, hot water, for example at temperatures of 200° F., and upwards, is supplied to the manifold 143 and is sprayed into the tank through the arms 143a and the openings 144.

As an example of the process, tobacco, in a tank having a temperature of 85° F., was subjected to a vacuum of 29.3 inches, after which five gallons of water at a temperature of approximately 200° F. was sprayed into the tank 10 over a period of one-half hour, this operation 15 raising the temperature to 95° F., and decreasing the vacuum to 28.75 inches. Another five gallons of water was then added over a period of thirty minutes, raising the temperature to 105° F., and 20 decreasing the vacuum to 28 inches. This temperature was then maintained for a period of one-half hour, during which slight amounts of water were added and then the vacuum broken.

In another example of the process, tobacco, in 25 a tank having a temperature of 90° F., was subjected to a vacuum of 29.6 inches and was then steamed with saturated steam to 125° F. This reduced the vacuum to 27.25 inches, and ten gallons of hot water were then added over a period 30 of one-half hour, which raised the temperature to 130° F. The tobacco treated was eight cases of binder tobacco.

In another instance, tobacco, in a tank having a temperature of 80° F., was subjected to a vacuum of 29.6 inches and was then steamed with saturated steam to 150° F., after which ten gallons of hot water were added, raising the temperature to 180° F. In this case the tobacco 35 treated was twelve bales of Manila filler.

In another instance, ten cases of binder tobacco were evacuated to an absolute pressure of 0.48 inch at 80° F. and then ten gallons of water added, raising the absolute pressure to 4.28 inches and the temperature to 145° F.

What I claim as new, and desire to secure by 45 Letters Patent, is:

1. A process for treating tobacco comprising subjecting the tobacco to a high vacuum, supplying to the evacuated tobacco a large amount of steam, condensing the steam upon the tobacco to raise its temperature and increase the pressure thereon, the steam being passed into but not through the tobacco, and then maintaining the tobacco in contact with the steam at substantially constant absolute pressure for a substantial time interval, while continuing to pass steam into but not through the tobacco.

2. A process for treating tobacco comprising subjecting the tobacco to a high vacuum, supplying to the evacuated tobacco a large amount of steam, condensing the steam upon the tobacco to raise its temperature and increase the pressure thereon, the steam being passed into but not through the tobacco, and then as a final step maintaining the tobacco in contact with the steam at substantially constant absolute pressure for a substantial time interval, while continuing to pass steam into but not through the tobacco.

JESSE C. McCORKHILL.
